UNITED STATES PATENT OFFICE

GILBERT J. ORMISTON, OF JUDSON, NORTH DAKOTA

DESIGN FOR A RIDING SPUR

Application filed April 13, 1931. Serial No. 39,458. Term of patent 7 years.

To all whom it may concern:

Be it known that I, GILBERT J. ORMISTON, a citizen of the United States, and a resident of Judson, in the county of Morton and State of North Dakota, have invented the new, original, and ornamental Design for Riding Spur, of which the following is a specification, reference being had to the accompanying drawings, forming part thereof.

Figure 1 is a plan view of a riding spur showing my new design, and

Figure 2 is a side view of the device shown in Figure 1.

I claim:

The ornamental design for a riding spur, substantially as shown.

Signed at Almont in the county of Morton and State of North Dakota this 3 day of April, 1931.

GILBERT J. ORMISTON.
